UNITED STATES PATENT OFFICE.

DAISY ORR MILLER, OF WASHINGTON, DISTRICT OF COLUMBIA, ASSIGNOR OF ONE-HALF TO MARIE HASELTINE, OF WASHINGTON, DISTRICT OF COLUMBIA.

TOILET ARTICLE.

1,107,977.

Specification of Letters Patent. Patented Aug. 18, 1914.

Application filed November 12, 1912. Serial No. 731,008.

To all whom it may concern:

Be it known that I, DAISY ORR MILLER, a citizen of the United States, residing at Washington, in the District of Columbia, have invented certain new and useful Improvements in Toilet Articles, of which the following is a specification.

This invention relates more especially to improvements in that class of toilet articles which are used for applying cosmetic or other powder to the face or other parts, and comprises a soft tab or pad of cotton or other soft fibrous material impregnated with the powder in such a way that it will not shake out over the clothes of the user as powder will do, for example, when applied with a powder puff or cloth in the usual way, but which will yield an abundance of powder when gently tapped. Individual tabs or pads of this kind made of aseptic material and put up in closed packages, as hereinafter described, constitute a very desirable substitute for the powder puff and receptacle generally found in ladies' toilets in public places, as well as providing an exceedingly attractive and useful advertising medium. Obviously, however, such an article is by no means limited to these uses alone.

In order to more fully describe my invention, reference will be had to the accompanying drawing, wherein,

Figure 1, is a perspective view of a sealed package, showing one way of dispensing my improved tabs; Fig. 2, a perspective view showing the outer closure of the package open and its contents removed and placed in line above it, and Fig. 3, a vertical section through the package shown in Fig. 1.

In an article of this kind it is particularly desirable that the powder should not easily drop off the tab when the latter is handled in use, and it is also important that a very small tab be capable of carrying or holding a relatively large amount of powder material. It is extremely difficult to get dry cotton to take up and hold face powder applied thereto in the dry state. The powder in this condition does not readily sink into the dry cotton, but banks up on the surface thereof. For this reason it is difficult to make a small piece of cotton hold a relatively large quantity of powder so that the latter will not too easily drop off when the powder is applied in the dry state to the cotton.

For the above reasons, among others, I preferably subject the cotton to a treatment of so-called "liquid face powder" by impregnating the whole body of the cotton or apply the liquid powder more superficially to one or more of its faces to form a coating. After the cotton is so treated it is allowed to dry. The powder is then thoroughly intermingled with the fibers of the cotton and will not too readily come off, that is, it will not fall of its own weight from the pad onto the clothes as from an ordinary powder puff, but will yield an abundance of powder when applied to the skin by gently patting or rubbing. The tabs may be cut into the desired shapes either before or after being treated with the liquid powder, or either before or after they dry.

One way of making these tabs is to select or form cotton batting of the desired thickness, cut this into squares such for example as shown, dip these squares of tablets into a bath of liquid face powder then allow the tablets to dry. But as above stated the cotton batting in bulk may first be treated with the liquid face powder and then cut into tablets of the desired shape either before or after the cotton dries, but preferably afterward. So-called "liquid face powder" is a commercial article of which there are several kinds on the market. I preferably employ aseptic liquid face powder of which there are also several kinds on the market.

In the accompanying drawings, 1 indicates one form in which these tabs may be made. I also preferably employ aseptic absorbent cotton such for example as surgical cotton. Cotton of this kind treated with aseptic face powder produces a thoroughly aseptic article and these qualities may be preserved by confining the tab in a sealed protective closure 2 preferably impervious to air and moisture. Such closure consists preferably of a waxed paper or other transparent envelop.

After the tabs are treated with the liquid powder and dried, I preferably sprinkle a small quantity of dry face powder on one or both of the broad faces of the tab, merely to show the tab contains powder. This, however, may be omitted if desired.

After the tabs are completed, each is preferably placed in a two leaf folder such as 3, consisting of a piece of paper or other suitable material having preferably more body

or stiffness than has the outer closure. I then place the two, the tab and the folder, within the closure 2, and seal the latter.

The folder 3 performs two functions. It 5 serves to carry on its outer face or faces such printed matter as the trade-mark of the article, the manufacturer's name and address, or advertising matter of any kind. The outer closure 2 being transparent enables one to readily read such printed matter on the inclosed folder. This folder at 10 the same time lends a stiffening to the package which better adapts it for stacking than were the tabs slipped into the outer 15 casing alone.

Articles of this kind may be very cheaply manufactured and therefore may be dispensed in public places at a very small price. Moreover, the articles are so inexpensive that they may be given away as advertisements for face powder or other merchandise or for other purposes. It should 20 be understood, however, that I do not limit myself to any special way of packaging the 25 article or applying the liquid powder to

the cotton, which may act as a vehicle therefor, or other material. It should also be understood that I use the term "face powder" in a generic sense which term also includes what is known as "talcum powder" 30 or other powders which are applied as cosmetics or otherwise to the human skin. The powder may also be applied to the cotton in a semi-liquid condition, and as an article it is within the scope of my invention 35 to apply the powder in any way.

What I claim is:—

A toilet article, comprising a tab of soft fiber impregnated with a toilet powder, the fibers of said tab forming a webbing intimately commingling with the mass of said powder and adhering thereto, whereby the powder is retained in said tab against falling therefrom by its own weight. 40

In testimony whereof I affix my signature 45 in presence of two witnesses.

DAISY ORR MILLER.
